UNITED STATES PATENT OFFICE.

HARRY G. WEEKS, OF CHICAGO, ILLINOIS, ASSIGNOR TO FREDERICK C. AUSTIN, OF CHICAGO, ILLINOIS.

ELECTRIC HEATING UNIT.

1,169,213.

Specification of Letters Patent. Patented Jan. 25, 1916.

Application filed January 10, 1912. Serial No. 670,418.

To all whom it may concern:

Be it known that I, HARRY G. WEEKS, a citizen of the United States of America, and resident of Chicago, Cook county, Illinois, 5 have invented a certain new and useful Improvement in Electric Heating Units, of which the following is a specification.

My invention relates to electric heating devices in general, such, for example, as 10 stoves and flat irons and other similar devices.

It relates more particularly to the heating unit or resistance employed in devices of this kind.

15 Generally stated, the object of my invention is to provide an improved and highly efficient construction and arrangement of the heating unit or resistance of an electric heating device.

20 Special objects are to provide a novel and efficient form of metallic heating unit of such character that it is practically self-insulating by reason of the natural oxid which forms on the surface thereof; to provide 25 a heating unit rendered flat in a novel and efficient manner; to provide a novel and effective arrangement whereby different degrees of heat may be produced at will; to provide a novel arrangement of the heating 30 unit whereby one pilot lamp is sufficient for the three degrees of heat; and to provide certain details and combinations tending to increase the general efficiency of the heating unit of a device of this particular character.

35 To the foregoing and other useful ends, my invention consists in matters hereinafter set forth and claimed.

In the accompanying drawings Figure 1 40 is a diagram indicating a flat iron provided with a flat heating unit embodying the principles of my invention. Fig. 2 shows the method of forming the coil on a mandrel. Fig. 3 is an end view of said coil before being flattened. Fig. 4 shows the method 45 of flattening the coil by rolling the convolutions thereof over upon each other. Fig. 5 is an edge view of a portion of the completed coil or heating unit.

As thus illustrated, and referring more 50 particularly to Figs. 1 to 5, inclusive, my invention comprises a heating unit A having convolutions α that lean over and rest upon each other—that is to say, overlap each other. The result of the formation is that

the said relatively displaced convolutions 55 have parallel axes that extend crosswise of the length of the flattened unit produced thereby. The said heating unit is preferably, and as a matter of further and special improvement, made of the metal called 60 "nicrome." I have discovered that by the use of this metal the convolutions of a coil may be crowded tightly together, and may thus be in engagement with each other, without short-circuiting. This is for the 65 reason that "nicrome" oxidizes and provides itself with a thin coating that serves as effective insulation. The flat heating unit A thus constructed may be made in various ways. As shown, the said heating unit is 70 produced by first winding the "nicrome" wire on the mandrel B, to form a helical coil with the convolutions thereof disposed about a common longitudinal axis. Then the coil is laid on a table and rolled down 75 by a roller C, the effect being not to crush the convolutions, but simply to tumble or lay them over upon each other, whereby the said convolutions overlap each other like the shingles of a house. The result is that the 80 convolutions are displaced relative to each other and are so twisted around that their parallel axes extend at an angle to the length of the heating unit. Thus the heating unit as a whole is rendered flat and more 85 effective in character, but the convolutions themselves are not flattened, but simply twisted into different planes or positions. This avoids sharp bends in wire which 90 might break the metal or weaken it and increase the resistance at certain points. In this way the convolutions engage each other, but the insulating oxid thereof is sufficient to prevent the current from jumping across from one convolution to another. Preferably, the conditions are such that the drop in 95 potential from one convolution to another is not more than six volts, and where the current is maintained for some time I find that three volts is even better. With these conditions the oxid insulation does not tend to 100 break down, even when the convolutions are tight together and in metallic contact with each other.

As shown in Figs. 4 and 5, the result of 105 the flattening operation is that the convolutions of the coil overlap each other shingle fashion, so to speak, and are not distorted

by abrupt or sharp bends therein. An abrupt bend in a wire is liable to increase the resistance at such a point, if the metal is stretched or broken or weakened by the abrupt bend, and in that event the coil is liable to burn out more quickly, as it may become overheated at the point where the resistance has been increased by the weakening of the metal. In my improved construction, however, the coils are not subject to abrupt or sharp bends in the wire and in addition there are no places in the coil where two portions of the wire extend parallel with each other. Thus the danger of burning out and short circuiting is reduced to a considerable extent.

What I claim as my invention is:—

1. An electric heating unit in the form of a coil of wire having the convolutions in-

clined and overlapping each other shingle fashion to avoid abrupt bends in the wire and provide a substantially flat resistance element for heating purposes.

2. An electric heating unit in the form of a coil of bare wire having the convolutions inclined and overlapping each other shingle fashion to avoid abrupt bends in the wire and provide a substantially flat resistance element for heating purposes, said convolutions being insulated from each other only by the superficial oxid of the metal thereof.

Signed by me at Chicago, Illinois, this 8th day of January, 1912.

HARRY G. WEEKS.
